[57] CLAIM

The ornamental design for a computer output printer, as shown and described.

DESCRIPTION

FIG. 1 is a perspective view taken from the top, front and right side of a computer output printer showing our new design;

FIG. 2 is a top plan view thereof;

FIG. 3 is a front elevation view thereof;

FIG. 4 is a rear elevational view thereof;

FIG. 5 is a right side elevational view thereof;

FIG. 6 is a left side elevational view thereof;

FIG. 7 is a bottom plan view thereof;

FIG. 8 is a perspective view taken from the top, front and right side of a second embodiment thereof;

FIG. 9 is a top plan view of FIG. 8;

FIG. 10 is a front elevational view of FIG. 8;

FIG. 11 is a rear elevational view of FIG. 8; and

FIG. 12 is a bottom plan view of FIG. 8.
